UNITED STATES PATENT OFFICE.

ARILD M. BRENN, OF CHICAGO, ILLINOIS, ASSIGNOR, BY MESNE ASSIGNMENTS, TO
W. H. MINER, INC., A CORPORATION OF DELAWARE.

SIDE BEARING.

Application filed December 5, 1923. Serial No. 678,565.

This invention relates to improvements in side bearings.

One object of the invention is to provide a simple and efficient, self-centering, body 5 bolster side bearing, including an anti-friction roller element, wherein the roller is returned to centered position by pendulum acting means.

A further object of the invention is to 10 provide a device of the character indicated, wherein the roller is provided with annular flanges at opposite sides thereof with which co-act a pair of pendulum elements for returning the same to centered position.

15 Other objects and advantages of the invention will more clearly appear from the description and claims hereinafter following.

In the drawings forming a part of this 20 specification, Figure 1 is a vertical, sectional view taken through the ends of a body and truck bolster of a railway car showing my improvements in connection therewith, and Figure 2 is a vertical, sectional view 25 corresponding substantially to the line 2—2 of Figure 1.

In said drawing, 10 denotes the upper portion of a truck bolster of a railway car and 11 the opposed lower part of a body bolster. My 30 improved bearing, as shown, is attached to the body bolster and the anti-friction element is normally spaced a slight distance from the truck bolster.

The improved bearing, as shown, comprises, broadly, a housing or retaining member A; an anti-friction element proper B; a pair of supporting fingers or pendulums C—C; a pivot pin D; a wear plate E within the housing; and a wear plate F attached 40 to the upper surface of the truck bolster.

The housing or retaining member A is in the form of a box-like casting and has an upper wall 12, spaced depending side walls 13—13 and spaced depending end walls 45 14—14. The member A is provided at the corners thereof with suitably perforated lugs 15—15 laterally projecting from the end walls, by which the same is riveted or otherwise secured to the body bolster. The 50 upper wall 12 of the housing is centrally downwardly offset as shown, the offset portion thereof being provided with a convex surface on its under side and to which the wear plate E is attached. The offset portion 55 of the wall 12 is provided centrally thereof

with a thickened portion 16 upwardly extending therefrom, bearing on the under surface of the body bolster. At the upper end, each side wall 13 is provided with a sector shaped opening 17 centrally thereof, the openings 17 in the opposite walls being in alinement and adapted to accommodate the fingers C for swinging movement. The thickened portion 16 of the top wall is cut away at opposite sides as clearly shown in Figure 2, thereby providing a flat surface 18 at each side of the housing spaced inwardly from the inner surface of the corresponding side walls.

The anti-friction element B is of the roller type. The roller B is provided at each end thereof with a laterally projecting, relatively heavy, annular, peripheral flange 19 for a purpose hereinafter described.

The fingers C are two in number and of like construction, each having an inwardly projecting boss 20 at the upper end and an inwardly projecting lug 21 at the lower end thereof. The fingers C are pivotally supported at opposite sides of the housing A by the pin D extending through alined openings in the thickened portion 16 of the wall 12 and the bosses 20 of the respective fingers, the opposite ends of the pin being headed over to retain the fingers in operative position. The fingers are thus pivotally supported for swinging movement in the recesses 17 of the side walls 13, the recesses each being of ample size to provide sufficient clearance to permit the necessary movement 90 of the respective fingers. The lug 21 at the lower end of each finger projects into the opening defined by the annular flange 19 at the corresponding end of the roller. Each lug 21 has the opposite sides thereof cut 95 away along upwardly converging planes, thereby providing a knife edge 22 at the upper side thereof adapted to engage with the inner wall of the upper portion of the corresponding annular flange 19 of the roller. The fingers C are so proportioned that they normally support the roller with its upper and lower portions spaced respectively from the wear plates E and F on the body and truck bolsters, as clearly shown in Figures 1 and 2.

The wear plates E and F are curved longitudinally on arcs of relatively long radius, the curvature preferably being such that a one-eighth inch rise is provided for the full 110

travel of the roller bearing element. The plate E is secured to the curved under-surface of the downwardly offset portion of the top wall 12 of the housing by rivets or any other suitable means and presents a downwardly curved surface adapted to co-act with the roller. The plate F is secured to the upper surface of the truck bolster by rivets or any other suitable fastening means, a 10 supporting block 23 having a convex upper surface being interposed between the plate F and the bolster.

On the approach of the bolsters toward each other, the lower side of the roller will 15 be brought into contact with the upper surface of the plate F on the truck bolster and the under-surface of the plate E will next be brought into contact with the upper side of the roller. During the relative approach 20 of the bolsters, the knife edges of the fingers will be moved initially out of contact with the flanges 19, as will be obvious. Upon relative radial shifting movement of the body and truck bolsters, the anti-friction element 25 B will be rolled, as for example, to the dotted line position shown at the left of Figure 1, the same being limited in its movement by engagement with the adjacent right hand end wall 14 of the housing, as shown by the 30 dotted line position of said end wall and indicated at 14^a. During the rolling movement of the element B, the fingers will be swung to the right by engagement with the flanges 19, as shown in dotted lines of Figure 35 1.

Upon separation of the bolsters, or removal of the pressure upon the anti-friction element, the fingers C, due to the weight of the roller then suspended thereby, will 40 swing to central position under the influence of gravity, and the roller, being supported by the flanges 19 on the knife edges 22 of the fingers for free swinging movement relative thereto, will also swing to centered position 45 with reference to the fingers.

From the preceding description, taken in connection with the drawing, it will be observed that, at the initiation of the return movement of the parts to normal position 50 upon removal of the actuating pressure, the pendulum fingers are free to swing toward their normal depending position and also, the roller is free to swing about the fulcrum points of the pendulums without interference with the lower bearing surface. In my arrangement, it will also be seen that the points of engagement between the pendulum fingers and the over-hanging flanges of the roller are constantly shifting so that 55 different portions of the surface of the roller are always being presented for service, to thereby prolong the life of the bearing. Another feature of my invention resides in the particular formation of the fulcrum support lugs 21. By converging the surface 60

upwardly to a fulcrum knife edge, it will be seen that greater clearance is left between the lugs and the over-hanging flanges, thereby permitting greater travel of the roller for a given swing of the pendulum elements, as will be observed from an inspection of the dotted line positions of the parts shown in Figure 1.

I have herein shown and described what I now consider the preferred manner of carrying out my invention, but the same is merely illustrative and I contemplate all changes and modifications that come within the scope of the claims appended hereto.

I claim:

1. In a side bearing, the combination with a housing; of an anti-friction roller within the housing, said roller having annular side flanges; a pair of fingers pivotally connected to said housing and provided with knife edge supporting means adapted to engage underneath the respective flanges at the upper side of the roller to swingingly support the same.

2. In a side bearing, the combination with a retaining member adapted to be secured to the underside of a body bolster and having an upper bearing surface; of an anti-friction rolling element proper; and means providing a pendulum support for said element from said retaining member when said element is in normal position and free from load, said means being disengaged from said element and becoming temporarily inoperative to support said element, said element having a bearing face co-operating with the pendulum means when load is applied to said element and again becoming operative to engage a different portion of said bearing face when the anti-friction element is moved a predetermined distance to either side of normal position, whereby the bearing portions of the roller are shifted to present new portions to engage with the bearing surfaces.

3. In a side bearing for railway cars, including a body and truck bolster having opposed bearing surfaces thereon, the combination with a housing; of an anti-friction element within the housing, said element having a curved supporting surface thereon;

and a finger pivotally connected to said housing and provided with a projection adapted to engage said curved supporting surface of the anti-friction element to swingingly suspend the same between said bolsters and normally spaced from both of said bolster bearing surfaces, said projection being disengaged from said supporting surface when the bolsters approach each other and the anti-friction element is placed under load to render said finger temporarily inoperative and permit the same to remain in a pendent position while so inoperative, and further permit engagement thereof with another portion of said supporting surface when the antifriction element has moved a

predetermined distance to either side of centered position.

4. In a side bearing, the combination with a bolster; of a retaining member mounted on said bolster and having a bearing surface; a rolling anti-friction element having an extended supporting surface remote from the center of rolling movement of said element, and a bearing surface adapted to engage said first named bearing surface, said bearing surface of the anti-friction element also adapted to be engaged by an opposed bolster; a pendulum element swingingly hung from said retaining member and having a supporting edge thereon engaging beneath said supporting surface to swingingly suspend the anti-friction element free of said first named bearing surface and the opposed bolster at all times except when under load, 20 the supporting means on said pendulum element and said bearing surface being arranged to permit movement of said anti-friction element to temporarily free said supporting edge of the pendulum when the anti-friction element is under load and permit rearrangement of said supporting edge with a different portion of the supporting surface of said anti-friction element when said last named element has been moved 25 30 a predetermined distance to either side of its centered position, thereby supporting said anti-friction element in a different position when the same is free from load, thereby presenting different bearing areas to said first named bearing surface and said opposed bolster.

5. In a side bearing of the character de-

scribed, adapted for use with body and truck bolsters of railway cars, the combination with means on said body and truck bolsters 40 presenting opposed bearing surfaces; of an anti-friction element adapted to co-act with said bearing surfaces when said bolsters approach each other, said element being movable to either side of centered position; pendulum means swingingly supported on the body bolster for centering said anti-friction element; and a connection between said pendulum means and said anti-friction element for normally supporting said 45 element in suspended position, spaced from the bearing surfaces of both the body and the truck bolsters, and permitting vertical movement of the anti-friction element to disengage the same from said connection, 50 whereby said anti-friction element is temporarily disengaged from the pendulum connection upon relative approach of the bolsters to permit the pendulum means to remain quiescent while said anti-friction element moves relatively thereto under load and said connecting means to re-engage with a different portion of said anti-friction element when said element is shifted to either side of centered position to bring a different portion of the bearing surface of the anti-friction element into co-operating relation with the body and truck bolster bearing surfaces when said anti-friction element is freed from load. 55 60 65 70

In witness that I claim the foregoing I have hereunto subscribed my name this 26th day of November, 1923.

ARILD M. BRENNE.
